UNITED STATES PATENT OFFICE.

HORACE P. WALTER AND KARL L. HULLSICK, OF NORFOLK, VIRGINIA.

AUTOMATIC SAFETY GATE.

Application filed June 8, 1927. Serial No. 197,321.

The present invention relates to automatic gates such as are used to guard railroad crossings and the like.

Objects of the invention are to provide a gate of the above character which will open automatically upon the exertion of pressure above a certain predetermined amount upon certain mechanism connected therewith, will remain open while the said pressure is being exerted and will close automatically when the said pressure is relieved.

Further objects are simplicity of construction, durability, cheapness of manufacture, and positiveness of operation.

15 A further object is to provide a construction of the above character in which the roadway will be entirely unobstructed by the mechanism of the device when the gate is open.

20 A still further object is the provision of an enclosing pocket for the gate into which the gate slides when opening and by which the slide mechanism of the gate is protected.

Still further objects and advantages for 25 the invention will appear from the following specification and claims and we do not wish to be limited in the scope of our invention except as we shall be limited by said claims.

In the drawings accompanying and forming 30 a part of this specification,

Fig. 1 is a view in elevation showing the position of the gate mechanism when the gates are closed.

Fig. 2 is similar to Fig. 1 showing the position of the mechanism when the gates are open.

Fig. 3 is a section on line 3—3 of Fig. 1, showing details of construction.

Fig. 4 is a plan view of the invention showing the hinging of the platforms together.

Fig. 5 is a section on line 5—5 showing the relation of the pocket, gate and gate post to each other, the view being on an enlarged scale compared with the other figures.

45 Referring to the drawings in detail, the same reference numerals designating the same parts throughout the drawings, 10 designates a roadway, 11 are posts located at either side of the roadway. Each post 50 consists of parallel spaced members 11^a connected at their upper end by a cap 12. Spaced from and in alignment with posts 11 are other posts 13 one on each side of the roadway. These posts also comprise spaced parallel 55 members 13^a and are spaced from the posts

11 approximately a distance equal to the width of the roadway between the posts 11.

Pivoted to the posts 13 near their upper ends are members 15 comprising pocketed housings for the gates, the pivotal means being of any suitable character as pins 14 and the said members lying between the members 13^a of the posts 13. The other end of each of the members 15 are designed to lie between the members 11^a of posts 11. The pocketed members are comprised of top and bottom rails 16 and 17 connected at their ends by end members 18 and 18^a the former constituting spaced members 18^b and 18^c and intermediate 65 of their ends by brace members 19 and 20 arranged in pairs and spaced apart a distance equal to the space between the members 18^b and 18^c. The top members 16 are in the form of enclosures having strips or flanges 21 constituting slideways extending inwardly toward each other from the side walls, but spaced apart centrally of the pockets a sufficient distance to form a slot extending longitudinally of the pockets to accommodate the upper portions of gates 22 which are slidably mounted in the pockets and are provided on either side with rollers 29 in coaxial opposition to each other and are so positioned as to roll upon the flanges 21 as tracks and to so support the gates within the pockets as to facilitate their sliding thereinto. The top and bottom portions pocket respectively at the forward and rear thereof at 16^a and 17^a, the former lying between the members 11^a and the latter between members 13^a. 75 80 85

The gates 22 consist of top and bottom rails 23 and 24 secured together at their ends by vertical members 25 and 26 and intermediate of their ends by members 27. The forward half of the gates are provided with cross members 28 forming an obstruction to animals when the gates are closed. The gates and their receiving pockets are of substantially the same length so that each gate may be totally received within its pocket when the gates are open leaving the roadway entirely unobstructed for the passage of vehicles. The approach to the gates consists of platforms 30 one on each side of the gates hinged to suitable abutments in the roadway at points spaced from the gateway as at 31. The platforms are normally inclined from their pivotal ends upwardly toward the gates when the gates are closed and are held in this position by the weight of the gates and pocket- 90 95 100 105 110

ets to which they are connected as will herein-after appear.

The platforms 30 are connected at their adjacent ends by a hinge construction 32 consisting of a rod 33 extending beyond both sides of the platforms and to which straps 34^b are pivotally secured. Other straps 34^a are secured to the platforms 30 and are pivoted at 34^a to the straps 34^b as shown in Figs. 3 10 and 5. The straps are arranged in pairs, one strap of each pair being connected to each platform. By this construction both platforms will be depressed simultaneously when a vehicle or the like moves onto either plat- 15 form. A movable cover plate 35 is provided which covers at all time the space between the platforms and serves to protect the hinge construction from the elements and at the same time preserves the continuity of the roadway. 20 The ends of the pocketed members 15 adjacent the roadway are connected with the platforms by means of chains 36 secured to the ends of the rod 33 which project beyond the sides of the platforms, the chains being 25 trained over pulleys 37 secured between the upper ends of the members 11^a of posts 11.

Suitable counterbalance weights 38 may be secured to the adjacent ends of the platforms to counterbalance the weight of the gates and 30 pockets and a bumper 39 may be placed beneath the rod 33 to break any shock due to heavy or sudden load placed on the platforms.

The operation of the device is as follows:

When the approach platforms are unin- 35 cumbered by vehicles or the like, the gates 22 will remain closed as shown in Fig. 1, but upon a vehicle or the like being driven onto either of the platforms, the same will be depressed carrying the shaft or rod 33 down- 40 ward and elevating the forward ends of the gate pockets 15, whereupon the gates 22 slide rearwardly into the pockets leaving an unob- 45 structed roadway. At the same time the platform on the other side of the gate is depressed due to the hinged connection with the one upon which the load is located. When on the other hand the load is removed from the platforms, the weight of the gates and pock- 50 ets will draw the adjacent end of the platforms upward to their original and normal position. The pockets will incline forwardly toward the roadway and the gates will slide to closed position.

It should be noted that the arrangement is 55 such that the pockets incline downwardly to- 60 ward each other when the platforms are free of load, a condition which insures the gates contacting with each other and closing the roadway completely and rearwardly down- 65 ward when there is a load on the platform; the inclination in either case being such as to insure the ready movement of the gates to the desired position. It will also be borne in 70 mind that the length of the gates is such that only half of the frame work thereof ever

leaves the pockets which construction insures positiveness of operation and makes for strength when the gates are closed.

Having described the invention what is claimed is:

1. A device of the character described con- 70 sisting of a platform pivoted at one end, a pocketed member pivoted at one end, a gate 75 slidable in said pocket, means connecting the free end of the pocketed members to the free end of the platform so that when the free end of the platform is depressed the free end of the pocket will be tilted upwardly, a substantial portion of the gate remaining at all times within the pocket. 80

2. In a device of the character described, a gateway having posts at either side, pul- 85 leys mounted on the upper ends of said posts, other posts in alignment with the first named posts and spaced therefrom a distance equal to the distance between the first named posts, pocketed members pivoted at one end re- 90 spectively to each of said second named posts, platforms forming approaches to said gateway pivoted in the roadway at their ends dis- 95 tant from said gateway, chains passing over said pulleys and connecting the ends of the pocketed members and of said platforms ad- 100 jacent the gateway, gates slidable in the pockets, the length of each gate being equal to the length of its respective pocket, the ar- 105 rangement being such that one half of the length of the gates remain at all times in their respective pockets. 110

3. A device of the character described, con- 100 sisting of a pair of platforms adapted to pivot at one end to a roadway, the adjacent ends of said platforms being pivoted together, posts on both sides of the roadway at the ends of the platforms adjacent each other, pulleys 105 at the upper ends of said posts, means connected to said platform and passing over said pulleys, pivoted means having pockets there- 110 in, slideways in said pockets, said pivoted means being attached to the means passing over the pulleys and gates having means slid- 115 able in said slideways, said gates being totally receivable in said pockets. 120

4. A guard for railway crossings or the like comprising a pair of posts, one on each side of the roadway, other posts in alignment with said first named posts and spaced a distance from the first named posts a distance equal to the distance between the first named posts, pocketed members pivoted to the sec- 120 ond named posts, pulleys at the upper ends of the first named posts, platforms hinged to each other adjacent said first named posts and to the roadway at their opposite ends, chains passing over the pulleys and connect- 125 ing the ends of the platforms and pocketed members adjacent the first named posts and gates slidable in said pockets. 130

5. A device of the character described con- 130 sisting of a platform pivoted at one end, a

- pocketed member pivoted at one end, a gate 5
slidable in said pocket, said pocketed member being of dimensions to receive the entire length of the gate therein, means connecting the free end of said pocketed member to the free end of the platform so that when the free end of the platform is depressed the free end of the pocketed member will be tilted upwardly, a substantial portion of the gate remaining at all times in said pocket.
6. A guard for road crossings comprising parallel posts located on each side of the roadway crossing the road to be guarded, posts spaced from the parallel posts a distance substantially equal to the width of the road and having spaced parallel portions, frames having pockets formed therein, said frames having one end pivoted between said parallel portions and their adjacent ends lying between the parallel posts, gates slidable in said pockets, and means operable from the roadway for tilting the adjacent ends of the said frames up and down to cause the sliding of the gates therein.
7. A guard for road crossings comprising parallel posts located at the sides of the crossing road, posts spaced from the pairs of posts in the same plane therewith and a distance therefrom substantially equal to the width of the said road, members pivoted at one end to said last named posts and having free ends lying between the parallel posts, said members having pockets therein, gates slidable in said pockets and totally receivable therein, half of the gates remaining at all times in their respective pockets, means for tilting the pivoted members from the crossing roadway.
8. A guard for road crossings including pocketed members arranged in a plane at right angles to and transversely of the crossing roadway, said pocketed members being pivoted to supports at a distance from the roadway equal to the width of the roadway and having their free ends adjacent said crossing sides of the roadway, slideways in the pockets of said members, gates totally receivable in said pockets and having rollers thereon adapted to ride on said slideways, a portion of each gate being slidable from its pocket across the roadway and substantially half of each gate remaining at all times in its pocket, and means for tilting said pocketed members to cause the sliding of said gates.
9. A safety gate for crossings consisting of a pocketed gate receiving member pivoted at one end, a gate slidably received in said pocket, the dimensions of said pocket being such as to receive the entire gate therein and means for tilting the free end of said member.
10. A safety guard for road crossings comprising pocketed members extending in a plane transversely of the crossing road and pivoted at one end, gates slidable in said pockets and adapted to extend from said pockets part way across said road and to abut each other when so extended, and means for tilting said members to cause said gates to slide therein.
11. A safety guard for road crossings comprising pocketed members extending transversely of the crossing road and pivoted at one end, gates slidable in said pockets and adapted to be projected therefrom each part way across said roadway and abutting each other when so projected to close the roadway, said gates being totally receivable within said pockets, and substantially half of each gate remaining at all times in its respective pocket.
12. An automatic safety gate for crossings comprising a pair of platforms having their opposite ends pivotally mounted in a roadway, the adjacent ends of said platforms having straps thereon pivotally connected to a transverse rod, a cover plate bridging the adjacent ends of said platforms and slidable relative to both of said platforms and gate members adapted to move across said roadway, and means associating said platforms with said gate members so that the gates will be moved across the roadway under the influence of the movement of said platforms.
- In testimony whereof we affix our signatures.
